UNITED STATES PATENT OFFICE.

JAMES F. ROWLEY, OF CHICAGO, ILLINOIS.

ARTIFICIAL-LIMB-LOCKING DEVICE.

Application filed October 5, 1927. Serial No. 224,138.

This invention relates to artificial limbs of the type in which the thigh and shin sections can be manually secured against relative angular movement in one direction.

5 The main objects of this invention are to provide an improved form of artificial limb wherein the shin and thigh sections can be locked against angular relative movement by the limb operating suspender; to provide an improved limb of this character in which the danger of buckling forward of the limb is entirely eliminated; and to provide an improved form of locking mechanism which is durable and substantial in construction and 10 economical to manufacture.

An illustrative embodiment of this invention is shown in the accompanying drawings, in which:

Figure 1 is a vertical section of the knee 20 joint portions of an artificial limb, the back check and locking mechanism being taken on the line 1—1 of Fig. 2.

Fig. 2 is an elevation of the improved locking mechanism with the suspender controls 25 left out for the sake of clearness.

Fig. 3 is a reduced front elevation of the artificial limb showing the limb operating suspender controls.

The construction shown herein is of the 30 same general character as that shown in my co-pending application Serial No. 201,353, filed June 25, 1927, with certain important improvements resulting from actual experience in the use of knee joint locking mechanisms. Heretofore, in the construction of artificial limbs wherein a flexible member had its two ends attached to the thigh section and the medial portion looped around locking mechanism carried on the shin section, 35 it has been found that in some instances where the wearer attempted to lock the section against relative angular movement while the sections were in pivotal movement at the time of locking, that the limb would sometimes buckle forward unless the wearer kept a strain on the operating suspender and locking means. This action of the limb is caused by the end of the flexible member attached to the rear of the limb pulling the 40 member through the locking mechanism in a direction which tends to break the grip of the cam lock on the flexible member and thus release the sections from locked position.

In the construction shown in the drawings, a thigh section 1 is pivotally connected by 55 a knee bolt 2 to a shin section 3 in the usual manner. A back check 4 in the form of a flat metal strap for limiting the relative angular movement of the sections in one direction, is secured at its lower end 5 to the inside rear wall of the shin section 3 by a wood screw 6 threaded in a pair of leather washers 7. The back check 4 extends forwardly and then upwardly into the lower end of the thigh section 1, the upper end 60 thereof being bent to surround and be journalled on the knee bolt 2 with the end thereof extending downwardly and rearwardly to form a bearing 8 for a pin 9 which carries a pair of forwardly extending cheek plates 10 65 and 11.

The forward ends of the cheek plates 10 and 11 have a double roller 12 journalled therebetween on a pin 13, thus providing a suspender bearing located in advance of the 70 knee bolt 2 and which is adapted to receive suspender thongs 14 of a limb-operating shoulder suspender 15. Means are provided for holding the thongs 14 in the grooved 75 wheels 12 at all times and comprise a sleeve 16 journalled on a pin 17 carried by the plates 10 and 11, in close proximity to the suspender bearing 12.

The suspended thongs 14 after passing around the roller 12 then lead upwardly and 80 to the rear, over the knee bolt 2, and then downwardly around a double roller wheel 18 carried by a flexible strap 19 which has its lower end secured at 20 to the exterior rear side of the shin section 3 in the usual manner. 85 The thongs 14 then pass outwardly through the customary slot in the rear of the lower end of the thigh section and lead upwardly for attachment to the shoulder suspender 15.

A flexible strap member 21 which may be 90 entirely of leather or of leather with a thin, flexible steel backing strip has its upper end attached by screws 22 or the like to the exterior surface of the knee portion 23 of the thigh section 1, the lower end thereof extending downwardly and rearwardly into the interior of the upper end of the shin section 3, such lower end hanging free and not being 95 attached to anything.

Means are provided for gripping the flexible member 21 and thus securing the shin 100

and thigh sections against relative angular movement in one direction, and comprises a forwardly projecting arm 24 riveted or otherwise rigidly secured to the back check 4 and having a pair of laterally disposed downwardly turned ears to carry a pin 25 upon which is journalled a cam 26 integrally formed with cam arm 27, the flexible member 21 being adapted to extend between the arm 24 and cam 26, so as to slide therethrough when the sections are angularly moved relatively to each other.

Means are provided for manually raising the cam arm 27 so as to cause the cam 26 to grip the member 21 and comprise a link 28 pivotally mounted on a pin 29 carried medially of and between the plates 10 and 11, said link passing through a suitable opening in an outstanding lug 29^A riveted to the back check 24. The lower end of link 28 is bifurcated as shown particularly in Fig. 2, the bifurcated arms 30 and 31 extending outwardly and then downwardly and then inwardly in the form of a stirrup, the ends 25 thereof embracing the outer end of cam lever 27 and having a pin 32 passing therethrough for pivotally connecting the link 28 to the cam lever 27.

Yielding means are provided for normally urging the link 28 downwardly, thus normally retaining the locking mechanism in released position, and comprises a coil compression spring 33 surrounding the link 28, which has one end bearing against the under side of the lug 29 and the other end thereof bearing against a washer 34 retained on the link 28 by a pin 35.

In the operation of this artificial limb, the user manipulates the thigh and shin sections 40 in walking in the usual manner by means of the suspender 15 and suspender thongs 14, thus simulating the natural movements of the human limb.

During this normal movement of the limb, the flexible member 21 slides backwardly and forwardly through the locking mechanism which is normally held in released position by the compression spring 33 pressing downwardly on the link 28.

In cases where it is desired to take a step forward while the sections are bent angularly with respect to each other, as for instance in walking up a steep hill or taking a step to a higher plane, the wearer lifts his shoulder an abnormal amount, thus raising the forward suspender bearing 12 upwardly and lifting the link 28 upwardly against the action of the compression spring 33.

Upward movement of the link 28 raises the cam lever 27 thus causing the cam 26 to grip the flexible member 21 thus securing the sections against relative angular movement in a forward or buckling direction.

Although but one specific embodiment of 65 this invention has been herein shown and de-

scribed, it will be understood that numerous details of the construction shown may be altered or omitted without departing from the spirit of this invention as defined by the following claims.

70

I claim:

1. An artificial limb comprising pivotally connected shin and thigh sections, locking means on one of said sections, a flexible member attached at one end only to the other of said sections and arranged to slide over said locking means when said sections are pivotally operated, and a suspender having connections for actuating said locking means to grip said flexible member and secure said sections against relative angular movement.

75

2. An artificial limb comprising pivotally connected shin and thigh sections, a suspender for operating said limb, a yielding bearing for said suspender located in advance of said pivotal connection, locking means on one of said sections, a flexible member attached to the other of said sections and arranged to slide over said locking means when said sections are pivotally operated, and connections between said yielding suspender bearing and said locking means for actuating said locking means to grip said flexible member and secure said sections against relative angular movement.

80

3. An artificial limb comprising pivotally connected shin and thigh sections, a back check secured to said shin section and journalled on said pivotal connection, a suspender bearing pivotally mounted on said back check, a suspender engaging said bearing for operating said limb, yielding means for said suspender bearing normally opposing the pull of said suspender, locking means on said back check, a flexible member attached to said thigh section and arranged to slide over said locking means when said sections are pivotally operated, and connections between said yielding suspender bearing and said locking means for actuating said locking means to grip said flexible member and secure said sections against relative angular movement.

95

4. An artificial limb comprising pivotally connected shin and thigh sections, locking means on one of said sections, a flexible member attached at one end only to the other of said sections and arranged to slide over said locking means when said sections are pivotally operated, a suspender having connections for actuating said locking means to grip said flexible member and secure said sections against relative angular movement, and automatic means for releasing said locking means.

100

5. An artificial limb comprising pivotally connected shin and thigh sections, a back check for limiting the relative angular movement of said sections in one direction, locking means on said back check, a flexible mem-

130

- ber attached to one of said sections and arranged to slide over said locking means when said sections are pivotally operated, and a suspender for actuating said locking means to grip said flexible member whereby said sections are secured against relative angular movement. 45
6. An artificial limb comprising pivotally connected shin and thigh sections, locking means on one of said sections, a flexible member attached to the other of said sections and arranged to slide over said locking means when said sections are pivotally operated, a back check, a lever pivotally attached at one end to the back check and having a suspender bearing at the other end thereof, a limb operating suspender engaging said bearing, 50 a link connecting said lever with said locking means, a back-check for limiting the movement of said sections in one direction, yielding means bearing between said link and said back-check normally holding said locking means in released position, said suspender being adapted to actuate said lever, link, and locking means to grip said flexible member and secure said sections against relative angular movement. 55
- 10 7. An artificial limb comprising pivotally connected shin and thigh sections, locking means on one of said sections, a flexible member attached to the other of said sections and arranged to slide over said locking means when said sections are pivotally operated, a back check, a lever pivotally attached at one end to the back check and having a suspender bearing at the other end thereof, a limb operating suspender engaging said bearing, a link connecting said lever with said locking means, yielding means normally holding said locking 60 means in released position, said suspender being adapted to actuate said lever, link, and locking means to grip said flexible member and secure said sections against relative angular movement. 65
- 15 8. An artificial limb comprising pivotally connected shin and thigh sections, locking means on one of said sections, a flexible member attached to the other of said sections and arranged to slide over said locking means when said sections are pivotally operated, a back check, a lever pivotally attached to the back check at one end and having a suspender bearing at the other end thereof, a limb operating suspender engaging said bearing, a link connecting said lever with said locking means, yielding means on said link normally holding said locking means in released position, said suspender being adapted to actuate said lever, link, and locking means to grip 70 said flexible member and secure said sections against relative angular movement. 75
- 20 9. An artificial limb comprising pivotally connected shin and thigh sections, a back-check for limiting the relative angular movement of said sections in one direction, a flexible member attached to said thigh section, means on said back-check for gripping said flexible member whereby said sections are secured against relative angular movement in the other direction, and a suspender having connections for causing said means to grip the flexible member. 80
- 25 10. An artificial limb comprising pivotally connected shin and thigh sections, a back-check for limiting the relative angular movement of said sections in one direction, a flexible member attached to the exterior knee portion of said thigh section, means on said back-check for gripping said flexible member whereby said sections are secured against relative angular movement in the other direction, and a suspender having connections for causing said means to grip the flexible member. 85
- 30 8. An artificial limb comprising pivotally connected shin and thigh sections, locking means on one of said sections, a flexible mem-
